UNITED STATES PATENT OFFICE.

VICTORIA L. MUNRO, OF HIGHLAND PARK, ILLINOIS

GARTER FOR KNICKERBOCKERS.

1,289,231.

Specification of Letters Patent. Patented Dec. 31, 1918.

Application filed September 10, 1917. Serial No. 190,546.

To all whom it may concern:

Be it known that I, Mrs. VICTORIA L. MUNRO, a citizen of the United States, and a resident of Highland Park, in the county 5 of Lake and State of Illinois, have invented a new and useful Improvement in Garters for Knickerbockers, of which the following is a specification.

This invention relates to apparel and 10 relates particularly to garters for supporting knickerbockers at the knees.

The object of the present invention is to provide garters for the purpose specified, so constructed and arranged that the act of 15 fastening the legs of the garment at the knees, will subject the garters to sufficient tension to hold the lower ends of the legs in adjusted positions. To this end, my improved garters comprise the various features 20 and details of construction hereinafter described and claimed.

In the accompanying drawing, in which my invention is fully illustrated,

Figure 1 is a bottom view of a leg of a 25 pair of knickerbockers or the like.

Fig. 2 is a side view thereof with the flaps at opposite sides of the slit therein turned back to expose the garter; and

Figs. 3 and 4 are views similar to Figs. 1 30 and 2, respectively, illustrating adjustable means for connecting the garter to the knee band of the garment.

As the garters for supporting opposite legs of the garment will be duplicates of 35 each other, a single description will apply to both and the accompanying description is, therefore, in the singular.

Referring now particularly to Figs. 1 and 40 2 of the drawing, 1 designates one leg of a pair of knickerbockers having a usual slit 2 in its lower end to provide for inserting the foot of the wearer therethrough and which is adapted to be held closed by any usual or suitable means, preferably by a button and button hole connection.

In accordance with my invention, the leg 45 1 is adapted to be held up or supported at the knee by a garter 3 made of suitable elastic material, opposite ends of which are attached to the knee band 4 of the leg at opposite sides of the slit 2, preferably closely adjacent to said slit, and, in use, is designed to

pass around the leg of the wearer underneath the knee band so as to be covered thereby, said garter being shorter than said 55 knee band, so that when said knee band is buttoned or otherwise fastened, this will draw said garter taut around the leg of the wearer, thus engaging the bottom of the leg 60 of the garment with the leg of the wearer so as to hold it in place, in the manner desired.

With the described construction, said garter 3 will also operate to draw the connected sections of the knee band at opposite sides 65 of the slit 2 and between the ends of said garter taut and will hold said knee band flat so that it will present a neat and attractive appearance.

A particular advantage of my improved 70 garter is that it does not obstruct the leg of the garment or interfere in any way with inserting the foot through the same, as in the case of a garter the ends of which are connected to form a continuous band.

My invention preferably contemplates the application of my improved garters to knickerbockers by manufacturers as a part of the garment. Also, my invention preferably contemplates the use of non-adjustable 80 fastening means for connecting the sides of the slit 2, preferably an ordinary button and button hole connection. In some cases this may involve a resetting of the button and a readjustment of the length of the 85 garters to fit legs which are not standard. These slight alterations are simple and involve very little work and can readily be made by any seamstress of ordinary skill.

As a modification of my invention, I contemplate making my improved garters adjustable in length, so that they may readily be made to conform to legs of different size, and in this way obviate all necessity for alterations. Simple means for this purpose 90 consists of forming a loop at one end of the garter which passes through a loop, preferably made of metal, attached to the knee band of the garment and the end of the loop formed in the garter being secured to the 100 main web of the garter by a buckle or the like.

This modification is shown in Figs. 3 and 4 of the drawings, in which 1' designates

a leg of a pair of knickerbockers or the like, 2' the slit therein opposite sides of which are adapted to be fastened together by a button and button hole, or other suitable means, 3' 5 is the garter, one end of which is permanently affixed to the knee band 4' of the garment at one side of and preferably closely adjacent to the slit 2'. Formed at the opposite end of said garter is a loop 5, the 10 free end of which is adapted to be secured to the main portion of the garter by a buckle, indicated at 6, and which extends through a loop 7 secured to the knee band of the garment.

15. Should it be found that there is a tendency for the garter 3 to fall away from the side of the knee band and to hang across and obstruct the leg opening when the garment is not being worn, so that, when the foot 20 is inserted through the leg of the garment, it is liable to catch on the garter, this can be obviated in a simple manner by attaching the garter to the knee band of the garment at a point or points between its ends. What 25 I now consider the preferable means for this purpose consists of one or more loops attached to the inner side of the knee band through which the garter passes so as to be freely movable endwise. This modification 30 is shown in Figs. 3 and 4 of the drawings, in which 8 designates a loop attached to the inside of the knee band 4' about midway between the points of attachment of the garter to said knee band, through which said 35 garter passes so as to be movable endwise.

By "knickerbockers" as used herein, I intend to include any form of knee pants the lower ends of the legs of which are slit and are provided with fastening means for connecting the edges of the garment at opposite 40 sides of said slits.

I claim:—

1. A garment comprising a tubular member the end of which is slit, means for detachably connecting the edges of said slit and a strip of elastic material applied to the inner side of the slit end of said tubular member and secured thereto at opposite sides of the slit therein at its ends only, 45 said strip of elastic material being designed and adapted to pass around the limb of a wearer inserted through said tubular member and the relation being such that connecting the sides of said slit will bring said strip into tension about the limb of a wearer and the relation being such also that when the sides of said slit are disconnected the slit end of said tubular member will be free to open, substantially as described.

2. A garment comprising a tubular member the end of which is slit, means for detachably connecting the edges of said slit and a strip of elastic material applied to the

inner side of the slit end of said tubular member and secured thereto at opposite sides 65 of the slit therein at its ends only, said securing means comprising detachable means at one end of said strip, said strip of elastic material being designed and adapted to pass around the limb of a wearer inserted 70 through said tubular member and the relation being such that connecting the sides of said slit will bring said strip into tension about the limb of a wearer and the relation being such also that when the sides of 75 said slit are disconnected the slit end of said tubular member will be free to open, substantially as described.

3. A garment comprising a tubular member the end of which is slit, means for detachably connecting the edges of said slit, 80 a strip of elastic material applied to the inner side of the slit end of said tubular member and secured thereto at opposite sides of the slit therein at its ends only, and means 85 for adjusting the operative length thereof, said strip of elastic material being designed and adapted to pass around the limb of a wearer inserted through said tubular member and the relation being such that connecting the sides of said slit will bring said strip into tension about the limb of a wearer and the relation being such also that when the sides of said slit are disconnected the slit end of said tubular member will be free 95 to open, substantially as described.

4. A garment comprising a tubular member the end of which is slit, means for detachably connecting the edges of said slit and a strip of elastic material applied to 100 the inner side of the slit end of said tubular member and secured thereto at opposite sides of the slit therein at its ends only, said strip of elastic material being designed and adapted to pass around the limb of a wearer inserted through said tubular member and the relation being such that connecting the sides of said slit will bring said strip into tension about the limb of a wearer and the relation being such also that when the sides 110 of said slit are disconnected the slit end of said tubular member will be free to open, and a loop on the garment between the attached ends of said strip of elastic material through which said strip passes, substantially as described.

5. Knickerbockers the legs of which comprise bands secured to the lower ends thereof, the lower ends of the legs of said knickerbockers being slit, means for detachably 120 connecting the edges of said slits and strips of elastic material applied to the inner sides of the bands at the lower ends of the legs of said knickerbockers and secured thereto at opposite sides of the slits therein at their 125 ends only, said strips of elastic material be-

ing designed and adapted to pass around the leg of a wearer and the relation being such that connecting the sides of said slits will bring said strips of elastic material into 5 tension about the leg of a wearer and the relation being such also that when the sides of said slits are disconnected, the slit ends

of said legs will be free to open, substantially as described.

In testimony, that I claim the foregoing 10 as my invention, I affix my signature this 31st day of August A. D. 1917.

VICTORIA L. MUNRO.
